(57) **CLAIM**

The ornamental design for a folding wireless charger, as shown and described.

DESCRIPTION

FIG. 1 is a front, right and top perspective view of a folding wireless charger, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged partial view of FIG. 5; and,

FIG. 10 is an enlarged partial view of FIG. 6.

In the drawings, the broken lines are for the purpose of illustrating portions of the folding wireless charger that form no part of the claimed design. In FIGS. 1, 2, and 5 through 8, the article is shown with a symbolic break in the length of its rod. The appearance of any portion of the article between the break lines form no part of the claimed design. In FIGS. 5, 6, 9, and 10, the dot-dash broken lines depict boundaries of enlarged portions of the article and form no part of the claimed design.
